UNITED STATES PATENT OFFICE.

FRANK D. HAYDEN, OF SEATTLE, WASHINGTON.

TIE PLATE.

1,411,626.

Specification of Letters Patent.

Patented Apr. 4, 1922.

Application filed May 31, 1921. Serial No. 473,590.

To all whom it may concern:

Be it known, that I, FRANK D. HAYDEN, citizen of the United States, residing at Seattle, in the county of King and State of Washington, have invented certain new and useful Improvements in Tie Plates, of which the following is a specification.

My invention relates to means for holding railroad rails and particularly to tie plates adapted to hold railroad rails to the ties.

An object of my invention is to prevent creeping of the rail longitudinally of the track.

Another object of my invention is to provide a structure in which the spikes holding the rail always remain in tight contact with the rail flange and never protrude when weight is placed on the rail.

A still further object of my invention is to enable part of the load on the rail to be borne by the spikes themselves, whereby part of the load on the upper surface of the tie is relieved, and the life of the wooden tie is prolonged.

Heretofore, in ordinary railroad construction after the ties had been in place for a short period of time the weight of the passing traffic caused the rails to become embedded in the upper surface of the tie and the spikes to protrude above the rail flange.

In my rail holding device under the rail flange and resting upon the top of the tie I provide a tie plate which has spike apertures therein. Adjacent the spike apertures are spike lugs adapted after the spikes are driven into place into the tie to be bent down and rest upon the head of the spike, thus insuring that any pressure on the plate will be transmitted to the spike. Rail holding lugs are also up-struck on the tie plate to hold the rail from slipping laterally of the track in one direction. Grip jaws prevent the creeping of the rail.

With these and other objects in view which may be incident to my improvements, the invention consists in the parts and combinations to be hereinafter set forth and claimed, with the understanding that the several necessary elements comprising my invention may be varied in construction, proportions and arrangements, without departing from the spirit and scope of the appended claims.

In order to make my invention more clearly understood, I have shown in the accompanying drawings means for carrying

the same into practical effect, without limiting the improvements in their useful applications to the particular constructions, which for the purpose of explanation, have been made the subject of illustration.

In the drawings:

Figure 1 is a top plan view of my device as applied to a railroad rail.

Fig. 2 is an end elevation of my device. 65

Fig. 3 is a side elevation of my device.

Fig. 4 is a detail of the grip jaw.

Fig. 5 is a cross section of my device taken on the line 5—5 of Fig. 1 and showing the position of the spike lugs after the tie plate 70 is in position.

In the drawings, I have shown a wooden railroad tie 1 upon which rests my tie plate 2. Bearing on the upper surface of the tie plate 2 are flanges 3 and 4 of a railroad rail 75 5. There are rail holding up-struck lugs 6 formed on one end of the tie plate 2 and adapted to bear against the flange 3 of the rail 5. These lugs are struck up from the body of the metal of the tie plate itself. 80

On one end of the tie plate 2 is provided a spike aperture 7 and adjacent the spike aperture is an upstanding spike lug 8. On the other end of the tie plate are spike apertures 9 and 11 respectively, and adjacent 85 these spike apertures are upstanding spike lugs 12 and 13, respectively. Adjacent the spike aperture 7 is an aperture 14 in the tie plate within which is adapted to fit a grip jaw 15. A lower gripping surface 16 of the 90 grip jaw 15 is formed of metal of the same thickness as the tie plate 1 and fits under the flange 3 of the rail 5. An upper gripping surface 17 is formed so that it will contact and bear against the upper surface of the 95 rail flange 3. The upper gripping element or surface 17 is of greater width than the aperture 14 in the tie plate and forms shoulders 18 which bear against the upper part of the tie plate when the grip jaw is in position.

A recess 19 passing through the bend between the upper gripping surface 17 and the lower gripping surface 16 is formed of such shape, that a spike 21 driven into the tie will have its head rest within the aperture 19 and bear against the upper gripping surface 17. The grip jaw is so constructed that the points of the gripping surfaces 16 and 17 are slightly tight at the entrance so that when the jaw is wedged in place the 110 flange 3 will be firmly gripped thereby. Spikes 22 and 23 are adapted to fit in spike

apertures 9 and 11 respectively, and to grip the rail flange 4.

In adjusting the rail 5 on the tie 1 the plate 2 is placed in position with the rail holding lugs 6 bearing against the flange 3 of the rail. The grip jaw 15 is in position within the aperture 14 in the plate; the spike 21 is driven down in place which forces the grip jaw to slide in a direction towards the center of the rail base. This causes the upper and lower gripping surfaces 17 and 16 respectively, to pinch the flange 3 tightly, and the spike 21 holds the grip jaw in its wedged position. Spikes 22 and 23 have been driven in place and the rail is now firmly held. Now, spike lug 8 is knocked down in the position shown in dotted lines in Fig. 5 and bears against the top of the spike 21. Lugs 12 and 13 respectively, are likewise bent down by hammer blow or otherwise to contact with the heads of spikes 22 and 23 respectively.

The pressure of traffic on the rail 5 is transmitted to the tie plate 2 and this through the bent down spike lugs 8, 12 and 13 is transmitted to the spikes 21, 22 and 23 respectively, thus minimizing the pressure of the tie plate against the tie 1. There can be no possible creeping of the rail 5 longitudinally of the track by reason of the grip jaw which firmly holds the flange 3 because of the natural spring of the metal of which the grip jaw 15 is constructed.

The life of a railroad tie employing my form of tie plate will be much longer than is customary and since the creeping of rails is effectually prevented the up keep of a system employing my device is comparatively small.

While I have shown and described the preferred embodiment of my invention, I wish it to be understood that I do not confine myself to the precise details of construction herein set forth, by way of illustration, as it is apparent that many modifications and variations may be made therein, by those skilled in the art, without departing from the spirit of the invention, or exceeding the scope of the appended claims.

I claim as my invention:

1. A device for preventing rails from creeping comprising a tie, a jaw provided with a recess and adapted to grip a rail flange by wedging, and a spike adapted to be driven into the tie to wedge the grip jaw against the rail flange, the head of said spike fitting within said recess.

2. A device for preventing rails from creeping, comprising a tie, having a lower gripping member adapted to fit under the rail flange, an upper gripping member having a recess therein and formed integral with the lower gripping member, and a spike adapted to be driven into the tie to wedge the upper and lower gripping members

against the rail flange, the head of said spike fitting within the recess in the upper surface.

3. A rail holding device comprising a tie, a single tie plate fitting against the rail, an upstanding integral spike lug on each side of the tie plate adapted to stand a bending strain, spikes to engage and hold the rail flange and to be held in place by the bending of the lugs upon their heads to cooperate with said lugs to take part of the load on the rail, and a grip jaw fitting through an aperture in the tie plate cooperating with one of the spikes adapted to be wedged against the rail flange to prevent slipping.

4. A rail holding device comprising a tie, a single tie plate fitting under the rail and having a greater number of spike holes on one side of the rail than on the other, upstanding integral lugs on the tie plate adapted to stand a great bending strain, spikes to engage and hold the rail flange and to be held in place by the bending of the upstanding lugs upon their heads, rail holding lugs on the side of the tie plate having the fewest spikes, said spikes and upstanding lugs cooperating with each other to take part of the load on the rail.

5. A rail holding device comprising a tie, a single tie plate fitting under the rail and having two spike holes on one side of the rail and one spike hole on the other side thereof, upstanding integral lugs on the tie plate adapted to stand a great bending strain, two spikes on one side of the rail flange held in place by the bending of the upstanding lugs upon their heads, one spike on the other side of the rail flange held in place by bending the upstanding lug upon its head, rail holding lugs on the side of the tie plate having but one spike, said spikes and upstanding lugs cooperating with each other to take part of the load on the rail.

6. A rail holding device comprising a tie, a single tie plate fitting under the rail and having two spike apertures on one side of the rail flange and one spike aperture on the other side, rail holding lugs on the tie plate on the side of the rail flange having one spike aperture, upstanding integral spike lugs on each side of the tie plate adapted to stand a great bending strain, and spikes adapted to hold the rail flange and cooperate with the spike lugs on the tie plate to take part of the load on the rail.

7. A rail holding device comprising a tie, a tie plate fitting under the rail, spike lugs on the tie plate, spikes adapted to hold the rail flange and cooperate with the spike lugs on the tie plate to take part of the load on the rail, and a grip jaw fitting through an aperture in the tie plate cooperating with one of the spikes adapted to be wedged against the rail flange to prevent creeping.

8. A rail holding device comprising a tie, a tie plate fitting under the rail, and having spike apertures therein, rail holding lugs on the tie plate, spike lugs on the tie plate, 5 spikes adapted to hold the rail flange and cooperate with the spike lugs on the tie plate to take part of the load on the rail, a grip jaw, a lower gripping surface on the grip jaw adapted to fit under the rail flange

through an aperture in the tie plate, and an upper gripping surface having a recess therein, into which one of the spike heads may fit to wedge the upper and lower gripping surfaces against the rail flange to prevent creeping.

15

In testimony whereof I affix my signature.

FRANK D. HAYDEN.
